UNITED STATES PATENT OFFICE

FAYETTE M. CONNER, OF FAIRVIEW, OKLAHOMA

WINDOW VENTILATOR

Application filed March 26, 1929. Serial No. 350,026.

This invention relates to an improved humidifier and ventilator for installation upon windows in homes and buildings and it has more particular reference to a device which is especially useful where the temperature is unusually high and the air is dust laden and dry.

Briefly described, the invention has reference to an appropriately shaped enclosure or casing, certain portions of which are imperforate and other portions of which are provided with fabric or cloth screens and a pipe structure is associated therewith and perforated to distribute water on the screen whereby to provide an effective air purifying, moistening and ventilating structure.

In carrying out the invention I have perfected an unusually simplified arrangement of details, arranged for compactness and convenience as well as economy in construction, the complete device being such as to facilitate installation and to otherwise fulfill the requirements of an invention of this class in a highly satisfactory manner.

Other features and advantages will become more readily apparent from the following description and drawings.

In the drawings:

Figure 1 is an end elevational view of the ventilator installed in the window, and projecting outwardly therefrom.

Figure 2 is an outside elevational view of the ventilator observing the same in the direction from right to left in Figure 1.

Figure 3 is a horizontal sectional view taken approximately upon the plane of the line 3—3 of Figure 2.

Figure 4 is a perspective view of the outside fabric screen.

Figure 5 is a perspective view of the water circulating and distributing pipe structure.

In the drawings, the enclosure or casing is generally designated by the reference character 6 and it is open on its inner and outer sides and of the configuration seen in Figure 1. It is of a size to occupy approximately one-half, and preferably the lower half, of the window. The window is generally designated by the reference character 7. The casing comprises a solid bottom 8, a solid top

9 and the ends are partly solid. The upper portion 10 cooperates with the lower portion 11, in forming a rectangular opening. Located in this opening is a vertically elongated screen generally designated by the reference character 12. This comprises a metal frame 13, suitable attaching brackets 14, and a cloth or fabric panel.

This is made of foraminous or porous absorbent material. The outside and larger screen is generally designated by the reference character 15 in Figure 4. This comprises a similar frame 16, and attaching bracket 17. This occupies a downwardly and outwardly inclined position and is fitted in the outer opening in the casing, referring to Figures 2 and 3. This allows the water to be spread uniformly by gravitation and capillary attraction.

Surrounding the upper imperforate end and the upper end portion of the screen 15 is the piping structure designated at 18 in Figure 5. This constitutes, broadly stated, a moisture distributor. It embodies a lower U-shaped portion, the bight of which is designated at 19 and ends at 20. These pieces 19 and 20 are perforated. The bight portion distributes water onto the screen 15 and the arm portion 20 distributes water onto the screen 12 at the opposite ends of the casing. The reference characters 21 designate a solid section or portion which joins the perforated horizontal portions 23 in the U-shaped part. This part or portion 23 is also apertured. The reference character 24 designates a valved hose for supplying water to the distributor.

When the device is installed in the window as shown in Figure 1, and the lower sash is raised, it is obvious that the air passing through the device is cleansed and cooled. The device acts as a combined ventilator and humidifier.

The valved hose 24 is used at periodical times to moisten the screens and thoroughly saturate them, whereby to remove dust particles. The water is distributed to the various porous cloth surfaces or screens in an efficient manner by the novel pipe arrangement. The moistened surfaces through which the

air is admitted will gather the dust atoms and the evaporation from the sun and wind will materially cool the air, the admission of which may be accelerated by the use of 5 a fan (not shown) placed in the window opening inside of the device, if desired.

It is thought that by considering the description in connection with the drawings, a clear understanding of the construction 10 and operation of the invention will be had. Therefore a more lengthy description is regarded as unnecessary.

It will no doubt be found expedient to deviate from certain specific features in some 15 respects, in carrying the invention into actual effect, but not from the general principle.

Various changes in the shape, size and materials coming within the field of invention claimed may be resorted to in actual practice, if desired. 20

I claim:

1. A combined ventilator and humidifier for windows comprising a casing embodying a solid bottom, solid top and end walls, said 25 casing being open at its outer side and open at its inner side, an inclined absorbent and porous screen supported in said open outer side, and moistening means for said screen, the end walls of said casing being provided 30 with openings, and additional screens in said end wall openings.

2. In a combined window ventilator and humidifier a casing comprising a bottom, a top and end walls, said casing thus defining 35 a frame like enclosure and being open at its inner and outer sides, said outer side being inclined downwardly from top to bottom, an inclined screen located in said outer side, said end walls having openings, and additional 40 screens located in said openings, all of said screens embodying foraminous cloth panels, and a valved apertured water distributing pipe structure surrounding the upper portion of said casing, and having portions cooper- 45 ative with said screens for distributing water thereon.

In testimony whereof I affix my signature.
FAYETTE M. CONNER.
